MICROPHONE

Edwin Severin, Berlin, Germany, assignor to Tele-funken Gesellschaft für Drahtlose Telegraphie m. b. H., Berlin, Germany, a corporation of Germany

Application August 4, 1934, Serial No. 738,460
In Germany August 26, 1933

6 Claims. (Cl. 179—119)

This invention relates to an improved microphone.

Whenever serious acoustic disturbances prevail in the transmitter room, as is true, for instance, of airplane cabins, engine rooms, or the like, it is a general custom to use the so-called laryngophone for electric voice transmission, particularly in radio intelligence transmission. However, the rendition of the voice is rather faulty inasmuch as sibilants and "explosive" articulations, which are essential for proper intelligibility, are not picked up by the larynx type of microphone. Also with the cheek-type of microphone it is impossible to obtain a favorable pick-up of articulated sounds for the reason that the sound is subject to great damping by the flesh of the cheek so that the diaphragm of the microphone is no longer excited sufficiently. This is particularly disadvantageous in regard to the high-frequencies whose acoustic energy is inherently low anyway.

Acoustic pick-up devices of this kind are preferably carbon microphones capable of a relatively high voltage provided that the natural period of the diaphragm has been chosen sufficiently low. However, the transmissible frequency band is as a result unduly curtailed in the upper frequencies ranges seeing that such oscillations as are located above the natural frequency of the diaphragm are practically not transmitted at all by the microphone.

Microphones in which the oscillatory diaphragm constitutes part of a magnetic circuit, similarly as in headsets, possess only a narrow frequency band so that sibilants are rendered by them only improperly.

Microphones of this kind are acoustic pick-ups which are sensitive or responsive to direct air-pressure variations so that they will easily respond to these. Indeed, the diaphragms are excited not only by the sound waves emanating from a person talking to the microphone, but also by waves arising at more or less great proximity so that they will be caused to oscillate also by these vibrations. In other words, acoustic stray noises will be included in the transmission and thus impair the reproduction to a considerable extent inasmuch as the stray noise level lies considerably above the voice level.

Now, according to this invention these drawbacks inherent in the conventional type of microphone are avoided by that a diaphragmless oscillable system of the electromagnetic or electrodynamic or electrostatic type which is subject to positive mechanical actions, is fitted on top of an oscillable structure or system. Magneto-electric systems offer this advantage over the electrostatic ones that it is easier to establish a connection between the oscillating part of the system and the coupling links. The vibrating masses of the sys-

tem as well as their surface are so small and are so shaped that, with suitable arrangement they can practically not be set in motion by direct air-pressure. This diaphragmless system will thus not respond to acoustic disturbing noises so that these latter will be kept out of the transmission.

Such a system together with a suitable coupling link is fitted on top of the skull at a point which is set in movement by the vibrations the frequency and amplitude distribution of which corresponds as closely as feasible to the acoustic voice. Inasmuch as the source or seat of sibilants and of explosive sounds is in the neighborhood of the upper jaw (incisors, palate), preferably a place is chosen in the vicinity of the upper jaw at which the bone is covered only by a thin and therefore but slightly damping or sound-deadening skin. Excellent pick-up points are the nasal bone, the cheek bone, the forehead and the teeth. When speaking the sound waves are transmitted by virtue of bone conduction through the coupling means to the oscillatory system. The transmissible frequency band of such microphones, especially within the higher frequency ranges, is essentially enlarged in contrast with other microphone constructions.

In the drawing a number of embodiments of the basic idea of the invention are illustrated. Fig. 1 shows in two views the microphone 1, which in this instance is strapped by ribbons 2 onto the head 3. The microphone is furnished with a permanent magnet 4 upon which the pole-shoes 5 and 6 are fitted. In the air-gaps 7, between the pole-shoes, the keeper 9 oscillates about the pivot 8, the said keeper 9 being surrounded by a coil 10. The voltages induced in the coil by the movements of the keeper are fed to an amplifier. Attached to the keeper 9 is the coupling means or link 11 which is likewise pivotable about 8. At its free ends it has a suitably formed or molded piece 12, the latter being fitted upon the nasal bone or bridge of the nose. When speaking, the sound waves are transmitted by virtue of bone conduction so that the bone of the nose experiences vibrations which are transmitted to the molded piece 12. The result is that the keeper or armature 9 is caused to move through the intermediary of the coupling links. Instead of two coupling links 11, only one may suffice. The microphone 1 is enveloped by the case 13.

In Figs. 2, 3, 4, and 6 parts are shown which are designated by the same reference numerals as in Fig. 1.

Referring more especially to Fig. 2, the coupling link 11 is shown arranged with the same magnetic field disposition as in Fig. 1, except that in Figure 1 the link 11 is fastened on the outside of casing 13 to the pivot point, whereas in Figure 2 the upper portion of the coupling link 11 forms the armature.

In the case of Fig. 3, with a magnetic system comprising the permanent magnet 4, pole-shoes 5 and 6 and the magnetic shunt 16 the keeper 9 is supported by means of a narrow connecting strip 15 which increases the yieldableness of the keeper, in the magnetic shunt 16. The coupling link 11 with the molded or fashioned piece 12 engages the keeper 9 directly outside the pivot thereof.

Fig. 4 shows another embodiment of the electromagnetic oscillation system in which the keeper 9 inside the two pole-shoes 5 and 6 is pivoted about the axis 8. At the axis 8 engages the coupling link 11 with the molded piece 12.

By virtue of the movements of the keeper, also in the embodiment shown in Figs. 2-4, voltages are induced. The oscillation system could consist also of a system furnished with a keeper oscillating anteriorly of the poles.

Fig. 5 shows an oscillatory system predicated upon the dynamic principle. The magnetic field is excited by the permanent magnet 17 with which are associated the additional iron paths 18 and 19. These form the annular air-gap 20 in which the winding 21 of the movable coil is able to move. The latter is guided, in turn, by the fixed coil-former 22 and the movable coil centering means 23. At the centering means movable coil 21 engages the coupling link 24 with the former or molded piece 25 which is generally similar to member 12 mentioned above except for the omission of the coupling link 11.

The molded pieces in these embodiments could also be given other suitable shapes than that to be applied to the nose, the latter to be chosen in accordance with the pick-up point. For example, one may substitute for the nose attachment another shaped molded piece for attaching to or application for another shaped piece for attaching to the cheek bones.

An embodiment of the object of this invention for picking up the sound on the teeth is shown in Fig. 6. The oscillation system 26 could be of a kind as hereinbefore illustrated rather than the one here shown. The system is encased by 13, the latter having a tubular attachment or extension 27 in which the coupling link 11 with the shaped or molded piece 12 moves. The latter projects through the opening 28 in the extension 27. Contacting between keeper 9 and the pole-shoes 5 and 6 is prevented by the rubber buffers 29 which at the same time insure proper damping of the system. The microphone is held like a smoker's pipe between the teeth.

I claim:

1. A microphone especially adapted for the transmission of voice subjected to acoustical disturbances comprising a casing containing a permanent magnet and an electro-magnet located within the field of said permanent magnet, an armature arranged within said electro-magnet, said armature having a pivot within and passing through the walls of said casing to provide an oscillating part which acts as a pickup point, said pivot being secured to a pair of links connected with a fashioned piece which adapts itself to contact with the bone structure of the human body, said pair of links located on each side of said casing and joined together at a junction point adjacent said fashioned piece.

2. A microphone especially adapted for the transmission of voice subjected to acoustical disturbances comprising an oblong casing having a tubular extension member, said casing contain-

ing a permanent magnet and an electro-magnet within the field of said permanent magnet, an armature arranged within said electro-magnet, a coupling link secured to said armature and located within said tubular extension member, said armature having a pivot within said casing to provide an oscillating part which acts as a pickup point, said pickup point consisting of a fashioned piece which adapts itself to contact with the teeth of the human body.

3. A microphone especially adapted for the transmission of voice subjected to acoustical disturbances comprising a casing containing a permanent magnet and an electro-magnet located within the field of said permanent magnet, an armature arranged within said electro-magnet, said armature having a pivot within and passing through the walls of said casing to provide an oscillating part which acts as a pickup point, said pivot being secured outside of said casing to a pair of links joined together at its free end with a fashioned piece which adapts itself to contact with the bone structure of the human nose.

4. A microphone especially adapted for the transmission of voice subjected to acoustical disturbances comprising a casing containing a permanent magnet and an electro-magnet located within the field of said permanent magnet, an armature located within said electro-magnet, said armature being connected to a movable shaft acting as a pivot within said casing passing through the walls of said casing, and an outside linkage system connected outside of said casing to the ends of said movable shaft, the free ends joined together at a junction point and joining a fashioned piece which is in contact with the bone structure of the human nose.

5. A microphone especially adapted for the transmission of voice subjected to acoustical disturbances comprising an oblong casing containing a permanent magnet and an electro-magnet located within the field of said permanent magnet, means for retaining said microphone to the head of the human body, an armature arranged within said electro-magnet, said armature being connected to a movable shaft acting as a pivot within said casing and passing through both walls of said casing to provide an oscillating part which acts as a pickup point, said pivot being secured to a pair of coupling link members connected with a fashioned piece which adjusts itself to contact the cheek bone of the human body, said pair of links located on each side of said casing and joined together at a junction point adjacent said fashioned piece.

6. A microphone especially adapted for the transmission of voice subjected to acoustical disturbances comprising a casing, a permanent magnet and an electro-magnet located within the field of said permanent magnet, an armature located within said electro-magnet, said armature being connected to a movable shaft acting as a pivot located within said casing and passing through both walls of said casing to provide an oscillating part which acts as a pickup point, a pair of links being connected outside of the casing to the ends of said movable shaft, the lower end of said links being connected with a fashioned piece which adapts itself to contact with the human skull, said pair of links located on each side of said casing and joined together at a junction point adjacent said fashioned piece.

EDWIN SEVERIN.
